ATTORNEYS.

UNITED STATES PATENT OFFICE.

THOMAS ADAM CLAYTON, OF PARIS, FRANCE.

APPARATUS FOR THE MANUFACTURE OF OXYGEN COMPOUNDS OF SULFUR.

1,364,716.

Specification of Letters Patent.

Patented Jan. 4, 1921.

Application filed April 2, 1920. Serial No. 370,846.

To all whom it may concern:

Be it known that I, THOMAS ADAM CLAYTON, a citizen of the Republic of France, and a resident of 48 Rue de la Victoire, Paris, France, have invented new and useful Improvements in Apparatus for the Manufacture of Oxygen Compounds of Sulfur, of which the following is a specification.

My invention relates to an apparatus for the manufacture of oxygen compounds of sulfur, and especially sulfur dioxid mixed with sulfur trioxid for use in disinfecting or in the destruction of parasites, insects or for other purposes.

My invention more particularly relates to an apparatus in which the air, required for the combustion, volatilization and oxidation of the sulfur, is forced into the sulfur combustion furnace at two different levels, in such a manner as to perform said operations in two steps: a first supply of air (primary air), provided at the lower part of the furnace, delivers the amount of air required for the combustion, and volatilization of the sulfur; a second supply of air (secondary air), provided above the first, in a chamber separate from the lower part of the furnace by one or more baffles, delivers the amount of air required for insuring complete oxidation of the sulfur vapors evolved and avoiding sublimation.

My apparatus is provided with any suitable means for directing the primary air toward the hearth or vessel in which burns the sulfur, while the secondary air is directed, by any suitable means, toward the outlet of the apparatus, so that the secondary air current may not interfere with the outflow of the gases carried over by the primary air current, thus avoiding the back flow of the said gases toward the hearth.

The annexed drawings show, by way of example, different forms of the said apparatus:

Figure 1 is sectional elevation on the broken line 1-1 of Fig. 2.

Fig. 2 is a horizontal section on line 2-2 of Fig. 1.

Fig. 3 is an axial sectional elevation of a modified form of apparatus.

Fig. 4 is a horizontal section on line 4-4 of Fig. 3.

Fig. 5 is an axial sectional elevation of another modified form of apparatus.

Fig. 6 is a horizontal section on line 6-6 of Fig. 5.

In Figs. 1 and 2, the apparatus consists of a cylindrical or other metal vessel A, hermetically closed by a cover A¹. B is the hearth or vessel in which is located the sulfur, C is the charging door, and D D¹ are baffles in any suitable number. The pipe E, leading in air forced by a fan, branches into two pipes E¹, E², of which one E¹ terminates slightly above the hearth B to which it delivers the air necessary to effect combustion of sulfur; the other pipe E² terminates at a higher level, between the baffles D D¹ and delivers the supplementary oxygen required for transforming completely the vapors of uncombined sulfur into SO₂ and SO₃. The pipes E¹ and E² are provided with registers E³ to allow the delivery of air to be so regulated that, on the one hand, the sulfur in the hearth does not burn too intensely, which would effect a more abundant vaporization of sulfur than is required and occasion a loss by sublimation, and, on the other hand, that the amount of oxygen passing into the apparatus through the pipe E² is sufficient to oxidize completely the uncombined sulfur vapors and entirely transform them into sulfur dioxid. Under these conditions, the gaseous mixture which passes out through the outlet tube F is as rich as possible in SO₂ and SO₃, and should not contain uncombined sulfur vapors, which may be easily insured by previously taking samples through the cock f.

The primary air current, flowing in through the pipe E¹, is directed toward the hearth by a deflector consisting in a sheet metal J, inclined to an angle of about 45°, secured in front of and above the primary air inlet.

A deflector G, arranged near the inlet orifice of the pipe E², has for its object to direct the current of air, forced in through said orifice, toward the outlet of the apparatus and to avoid a back flow, by said current of air, of the gases carried over by the primary air current. Said deflector consists (Figs. 1 and 2) in a parallelepipedic box G, secured against the wall of the vessel A, near and around the inlet orifice of the secondary air current; this box G is open but on one face, i. e. on the face turned toward the outflow of the apparatus G1 in such manner as not to interfere with the outflow of the gases carried over by the primary air current; both currents are thus directed in the same sense.

• In the modification shown in Fig. 3 and 4, the primary and secondary air are forced into the apparatus through one and the same pipe; the common orifice is divided, by the baffle D, into two juxtaposed inlets; the upper part, H², is designed for the secondary air supply and represents about one third of the total area of the opening; the lower part H¹, representing the two-thirds of the area 10 of said opening, is for the supply of the primary air current.

Said primary air current, forced in through the orifice H¹, is, as in Figs. 1 and 2, directed toward the burning sulfur on the 15 hearth B, by means of a deflector plate J, inclined to an angle of about 45° from the baffle D and extending a little beyond the lower edge of the orifice H¹.

The deflector of the secondary air current 20 consists in a curved sheet metal I, secured to the baffle D in front of the orifice H² at a certain distance therefrom, and extending to the wall of the vessel A, on either side of said orifice H²; the secondary air current 25 strikes against said deflector and cannot escape but upward, as shown in I¹, so as not to interfere with the outflow of the gases carried over by the primary air current, of which gases it completes the oxidation into 30 SO₂ and SO₃.

In Figs. 5 and 6 is shown another modification, in which the primary air is let into the apparatus through a pipe K, extending into the vessel A and through the same, said 35 pipe being provided with a series of perforations K¹, arranged in such a manner as to direct the current of air in a series of streams, inclined to an angle of about 45°, toward the hearth B; the secondary air is 40 forced into the vessel A through a pipe L, which may be branched on the pipe K; this pipe L extends into and through the vessel A, parallel to the pipe K, between the baffles D D¹; this pipe L is provided with a series 45 of perforations L¹, arranged on the part of the pipe turned toward the outlet of the apparatus; these perforations might also be arranged on the upper part of the pipe L, or in a plane inclined on an angle of about 50 45° upward.

The perforations K¹ and L¹ may be of variable size, according to their location on the pipes K and L, in such a manner as to compensate for the loss of pressure.

55 It is obvious that any other means might be employed for directing the primary and the secondary air current respectively toward the sulfur in the hearth and toward the outlet of the apparatus.

60 What I claim is:

1. An apparatus for the manufacture of oxygen compounds of sulfur, and especially sulfur dioxid mixed with sulfur trioxid, comprising a vessel, a hearth for the combustion of sulfur within said vessel, baffles

above said hearth, a primary air supply for the combustion and volatilization of sulfur in the lower part of said vessel, a secondary air supply, above at least one of said baffles, said air being adapted to complete the oxidation of the sulfur vapors evolved by the combustion of the sulfur, means for forcing the primary and secondary air currents into said vessel, means for regulating said air supplies, together with means for directing the primary air current at its inlet toward the hearth, and means for directing the secondary air current, at its inlet into said vessel, toward the outlet thereof. 70 75

2. An apparatus for the manufacture of oxygen compounds of sulfur, and especially sulfur dioxid mixed with sulfur trioxid, comprising a vessel, a hearth for the combustion of sulfur within said vessel, baffles above said hearth, a primary air supply for 80 the combustion and volatilization of sulfur in the lower part of said vessel, a secondary air supply, above at least one of said baffles, said air being adapted to complete the oxidation of the sulfur vapors evolved by the 85 combustion of the sulfur, means for forcing the primary and secondary air currents into said vessel, means for regulating said air supplies, together with a deflector plate located near the primary air inlet into said 90 vessel and directing the primary air current toward the hearth, and a deflector, located near the secondary air inlet into said vessel and directing the secondary air current toward the outlet. 95 100

3. An apparatus for the manufacture of oxygen compounds of sulfur, and especially sulfur dioxid mixed with sulfur trioxid, comprising a vessel, a hearth for the combustion of sulfur within said vessel, baffles 105 above said hearth, a primary air supply for the combustion and volatilization of sulfur in the lower part of said vessel, a secondary air supply, above at least one of said baffles, said air being adapted to complete the oxidation of the sulfur vapors evolved by the 110 combustion of the sulfur, means for forcing the primary and secondary air currents into said vessel, means for regulating said air supplies, together with a deflector plate 115 located near the primary air inlet into said vessel and directing the primary air current toward the hearth, and a deflector, comprising a parallelepipedic box, open but on one face, located near the secondary air inlet into said vessel and directing the secondary air current toward the outlet. 120 125

4. An apparatus for the manufacture of oxygen compounds of sulfur or the like, comprising a vessel having a hearth for the combustion of sulfur within said vessel, baffles above said hearth, a primary air supply for the combustion and volatilization of sulfur in the lower part of said vessel, a secondary air supply above said primary air 130

supply and at least one of said baffles, said air being adapted to complete the oxidation of the sulfur vapors evolved by the combustion of the sulfur, and means for forcing 5 the primary and secondary air currents into said vessel toward the outlet and against back flow.

In testimony whereof I have signed my name to this specification.

THOMAS ADAM CLAYTON.
